UNITED STATES PATENT OFFICE.

CHARLES H. LARSON, OF NEW YORK, N. Y.

ELECTRICAL APPLIANCE FOR ACTUATING AND CONTROLLING DUMB-WAITERS.

1,057,383.

Specification of Letters Patent. Patented Mar. 25, 1913.

Application filed July 18, 1911. Serial No. 639,078.

To all whom it may concern:

Be it known that I, CHARLES H. LARSON, a citizen of the United States, residing in the borough of Manhattan, in the city, county, and State of New York, have invented certain new and useful Improvements in Electrical Appliances for Actuating and Controlling Dumb-Waiters, of which the following is a specification.

10 The object of my invention is to afford simple but effective means adapted to be applied to dumb-waiter outfits already in use as well as to be embodied in new outfits, whereby the dumb waiter may be positively and safely operated and controlled by electricity.

15 The invention consists in the specific construction and arrangement of parts, circuits and connections hereinafter described and 20 claimed, a distinguishing feature being the means employed for automatically opening or cutting out either the elevating circuit or the lowering circuit when the other circuit is in actual use, as fully set forth.

25 The accompanying drawing is a diagrammatic representation of my system, the parts being drawn more or less symbolically, it being understood that I do not limit myself to the identical relative arrangement of circuits and parts shown since it is obvious that various modifications may be resorted to with like result and without departing from the spirit and intent of my invention in this respect.

30 With this understanding, M, represents a motor of any suitable form and type connected directly by the conductor m, with the + source of electricity, the negative conductor — being represented by n, said lines 35 m, and n, indicating the main line. Any desired source of electricity may be utilized, as, for instance, an ordinary plug connection with an electric light or power circuit, as may be most convenient or expedient. A 40 second direct motor wire a', connects the motor M, with the electro-magnetic relay A; and a third direct motor wire b', connects it with the electro-magnetic relay B.

The coils of the relay A, are connected 45 by the conductor a², with the stationary contact a³, and in like manner the coils of the relay B, are connected by the conductor b², with the stationary contact b³. The contact on the armature B', is in electrical connection through the conductor a⁴, with the yieldable terminal contact a⁵, connected nor-

mally with the wire n, of the main line. Similarly the contact on the armature A', is in electrical connection through the medium of the conductor b⁴, with the yieldable terminal contact b⁵, normally electrically connected with the branch conductor n', of the — wire n, of the main line. The conductor b⁴, also connects with the branch wire b⁶, through the medium of push buttons d, interposed in the cross connections. Push buttons u, and cross connections are also interposed between the parallel branches of the conductor a⁴, a⁴.

On the armature shaft m', of the electric 70 motor M, is mounted a gear wheel m², which meshes with a gear w, on the worm shaft W, which is journaled, preferably, in the sides of a cast iron box C, in which is also mounted a worm gear G. Rigidly secured to the 75 shaft g, of this worm gear G, and external to the box C, is the drum J, to which the hoisting rope h, is secured, said rope passing over the pulley I, and being secured to the dumb waiter E.

80 The parts d, u, represent push buttons or any equivalent circuit closing and opening devices, and are positioned so as to be conveniently operated on each floor of the building adjacent to the dumb waiter shaft 85 and openings therein. On pressing any one of the push buttons u, the "up" circuit m, M, a', a², a³, a⁴ and n, is closed, thereby actuating the motor M, rotating the worm shaft W, wheel G, and drum J, to wind 90 the rope h, and elevate the dumb waiter E—the push button being held depressed until the dumb waiter is opposite the particular shaft opening desired, and then released, breaking the circuit named, and 95 thereby stopping the motor M—the worm gearing holding the dumb waiter in position. The closing of the "up" circuit m, M, a', a², a³, a⁴, n, as set forth also energizes the electro-magnets of the relay A, causing 100 them to draw the armature A', away from the fixed contact b³, thereby breaking the "down" circuit m, M, b', b², b³, b⁴, b⁶, and n, and holding it open as long as the "up" circuit is closed, so that in the event of the 105 depression of any of the push buttons d, (or of any of the push buttons u, for that matter, other than that first depressed as above described) the said "down" circuit n, b⁶, b⁴, b³, b², b', M, and m, will be inoperative and remain so until the "up" circuit is again opened automatically by the release 110

of the push button a_1 , first named. When both circuits are open, and one of the push buttons d_1 is depressed, the operation is reversed, the "down" circuit m, M, b_1', b_2', b_3' , b_4, b_5 , and n , being closed, and the motion of the motor M , reversed, unwinding the rope h , from the drum J , and lowering the dumb waiter E —the closing of the circuit also energizing the electro-magnets of the relay B , and drawing the armature B' , away from the fixed contact a_3 , thereby rendering the "up" circuit $m, M, a_1', a_2, a_3, a_4$, and n , inoperative as long as the said "down" circuit is closed. It will thus be seen that absolute safety is assured, since the closing of one circuit cuts out the other automatically for the time being, *i. e.*, as long as the first said circuit remains closed and operative. Hence the dumb waiter may be controlled effectively from any one of several floors or stations, and the effects of interference (otherwise possible) are eliminated.

To avoid all possibility of accident through carelessness or mischief I provide safety terminal switches a_5, b_5 , so that in the event of the dumb waiter traveling to either extremity of its shaft it will open either one circuit or the other as the case may be and thereby stop the motor M , by reason of the engagement of one or the other of the contacts e, e , on the dumb waiter with either the spring switch a_5 , or b_5 , as will be readily perceived by reference to the drawing.

My means of controlling and operating a dumb waiter are so simple and inexpensive as to be readily applicable to outfit already in use as well as to those to be installed.

Furthermore, the running gear is so small and compact that the dumb waiter may be lowered to the fullest extent, the drum J , and connections occupying much less space than the hoisting wheels and running gear heretofore used, and which they are designed to supersede.

What I claim as my invention and desire to secure by Letters Patent is,

In electric apparatus of the character designated, the combination of a dumb waiter, actuating means therefor, a motor, two electric circuits arranged in connection with said motor to drive it in opposite directions, a relay in one of said circuits, a relay in the other circuit, means whereby when one is closed the other is open, yieldable terminal contacts normally electrically connected with the main line circuit and adapted to be opened by the dumb waiter at its upper and lower limits of travel, push buttons in sets, one set for each circuit, one for closing one circuit for actuating the motor to elevate the dumb waiter and energizing magnets of one relay to break the other circuit for holding the one circuit inoperative until the other circuit is broken, another set of push buttons whereby when both circuits are open and one of the latter push buttons depressed, the movement of the dumb waiter is reversed, and means on the dumb waiter for coöperation with said yieldable terminal contacts whereby one circuit or the other is opened automatically to stop the movement of the dumb waiter.

CHAS. H. LARSON.
